[57] CLAIM

The ornamental design for a housing for a transcutaneous electronic nerve stimulator, as shown and described.

DESCRIPTION

FIG. 1 is a top perspective view of a housing for a transcutaneous electronic nerve stimulator showing my design;

FIG. 2 is a top plan view thereof;

FIG. 3 is a side elevation view thereof;

FIG. 4 is a bottom plan view thereof; and,

FIG. 5 is an end elevation as seen in the direction of lines 5—5 in FIG. 3.

FIG. 1.

FIG. 5.

Fig. 2.

Fig. 3.
